UNITED STATES PATENT OFFICE.

THOMAS SPENCER MILLER, OF SOUTH ORANGE, NEW JERSEY, AND LOUIS G. RUGGLES,
OF NEW YORK, N. Y.; SAID RUGGLES ASSIGNOR OF HIS ONE-HALF TO LIDGERWOOD
MANUFACTURING COMPANY, A CORPORATION OF NEW YORK.

LOAD-TRANSFER APPARATUS.

1,228,344.

Specification of Letters Patent.

Patented May 29, 1917.

Application filed June 3, 1913. Serial No. 771,399.

To all whom it may concern:

Be it known that we, THOMAS SPENCER MILLER and LOUIS G. RUGGLES, citizens of the United States, and residents, respectively, of South Orange, in the county of Essex, State of New Jersey, and New York city, borough of Manhattan, in the county of New York, State of New York, have invented certain new and useful Improvements 5 in Load-Transfer Apparatus, of which the following is a specification.

Our invention relates broadly to new and useful improvements in load-transfer apparatus, and more particularly contemplates 15 means for hoisting and transferring loads from a vessel to a dock or wharf, or vice versa, although we desire it understood that we do not desire to be limited to such use, as the invention may readily be employed 20 for hoisting and transferring loads from one vessel to another, or from one point to another on land.

The primary object of the invention is to provide a simple and efficient apparatus for 25 transferring loads which will have an increased capacity over any other apparatus of which we are aware, so as to reduce materially the time and expense incurred in unloading a vessel, or in loading the same. 30 Another object is to provide an apparatus including two or more hoisting and transferring lines in which one may always be employed to hoist and transfer the load while the other is returning from the point 35 of deposit to the point where it receives its load.

A further object is to provide an apparatus including two or more hoisting ropes, each of which will be provided with its own 40 actuating engine and in which said actuating engines may have the power thereof combined to act on one of said ropes in case it is desired to lift a load in excess of the power of the engine for that rope.

45 Other objects will appear during the progress of the description of a preferred embodiment to follow hereinafter.

To the ends above stated one embodiment 50 of the invention may consist of two or more hoisting ropes suspended from an elevated

support on a vessel, and extending over said support to independent winding engines, preferably mounted on the wharf or dock, which engines are capable of independent operation to pay out and take up their respective ropes, but which may be combined or coupled so that they may exert their combined power to take up one of said ropes, the fall of each of said ropes passing through a swinger frame, which frames are 55 operable by inhaul and outhaul lines to swing the hoisting ropes from the point where they are attached to the load to the point of deposit and to return them for a new load. The swinging means for the 60 frames is preferably common to both and so constructed and arranged that the frames are operated to simultaneously swing the 65 hoisting ropes in opposite directions to each other so that, when one rope is being swung 70 to transfer its load to the point of deposit another rope is being returned to the point where it is to take its load.

The invention further consists in the arrangement and combination of parts and 75 mechanisms in operative combination to be more fully described hereinafter, and the novelty of which will be particularly pointed out and distinctly claimed.

We have fully and clearly illustrated a 80 preferred embodiment of the invention in the accompanying drawings to be taken as a part of this specification and wherein:

Figure 1 is a view showing in elevation a complete apparatus for transferring loads 85 from a vessel to a dock, the vessel being shown in section, and the general direction of travel of the load being shown in dot-and-dash lines.

Fig. 2 is a view in side elevation of a 90 swinger frame forming part of the invention.

Fig. 3 is a top plan view, partly in section, of the swinger frame shown in Fig. 2.

Fig. 4 is a top plan view, partly in section, of a duplex winding engine for operating on the hoisting lines or the swinging lines employed in the system.

Fig. 5 is a view in end elevation of the engine shown in Fig. 4.

Fig. 6 is a detail top plan view, partly in section, of a coupling means for connecting the motors for driving the drums shown in Fig. 4, so that both motors may exert their power upon one of the drums.

Fig. 7 is a front view of the superstructure shown in side elevation to the left of Fig. 1.

Fig. 8 is a diagrammatic view of the rope-leads in the system.

Referring to the drawings by characters of reference, 1 designates generally a wharf structure, and 2 designates a vessel, between which the load-transferring operations are 15 to take place, it being understood that the apparatus as hereinafter described may be used either for transferring the load from the vessel to the wharf or from the wharf to the vessel.

20 On the wharf is a superstructure 3 which may serve as a support for the rope-operating engines and such appurtenances to the ropes as it may be desired to locate upon the wharf. This structure forms no part of our 25 present invention, and is illustrated merely in order that the details and operation of the invention may be clearly understood.

The vessel 2 specifically forms no part of our invention, but may consist of the usual 30 hull having a hatchway 4 through which the load is passed in being deposited in, or withdrawn from, the hull. The deck of the vessel is indicated at 5 and carries a vertical mast 6 to which are pivoted in any suitable 35 manner booms 7, 8, provided with suitable guys or stays 9 to the mast and the hull whereby said booms may be adjusted to the desired position. The boom 7 carries at its 40 outer end a pair of suspension blocks, sheaves or other suitable rope guides 10, said boom being preferably arranged so that its outer end is located between the hatchway and the dock and extending above the hatchway. Extending over each of the blocks or 45 guides 10 is a hoisting rope, said ropes being shown respectively at 11, 12, the falls of said ropes depending from said guides 10, and being provided at their lower ends with suitable hooks 13, or any other means for attaching them to or lifting the load. These 50 ropes 11, 12, pass over guide-blocks 14 on the superstructure 3 and thence to winding drums 30, 31, to be described hereinafter, which are capable of operation independently of each other to take up and let out 55 their respective ropes, and which are each provided with motors which may be coupled to drive one of the drums when increased power is desired for either of the hoisting lines. The construction of these engines and motors will be described with greater detail hereinafter.

Engaging the fall of each of the hoisting lines is a swinger frame, shown respectively 60 at 15, 16, corresponding ends of said frames

being connected by a line 17, doubled upon itself and which passes over the rope-guide 18 carried by the outer end of the boom 8, which is preferably arranged so as to project outboard of the vessel in a direction 70 away from the wharf. Connected to the opposite ends of the swinger frames from the ends to which the rope 17 is connected, are hauling lines 19, 20, respectively, by means of which the swinger frames are 75 hauled outboard of the vessel toward the dock, the said lines 19, 20, being wound respectively upon winding drums 30^a, 31^a, preferably in reverse direction, so that, when one of said lines is wound on its drum, 80 the other is paid out, said drums being preferably interconnected so that they are positively driven to pay out and take up said lines.

The length of the rope 17 is preferably 85 definitely ascertained so that the swinger frames will bear a definite relation to each other as to the point where the load is taken up by one hoisting rope and the point where it is discharged by the other hoisting 90 rope, so that, when one hoisting rope is in position to be hooked onto its load the other is in proper position to deposit its load. In other words, when one hoisting line is in position to be attached to a load in the vessel, the other hoisting line is in position to deposit on the wharf a load previously 95 hoisted from the vessel.

The swinger frames referred to may take a number of forms within the purview of 100 our invention, but they preferably consist of parallel side plates 21 connected at their ends by yokes 22, 22^a, pivoted to said plates, and to which the ropes 17, 19 and 20, are adapted to be connected. Journaled upon 105 suitable bearings in said side plates are rope sheaves 23, 23^a, between which the hoisting rope is adapted to freely pass when being either taken up or paid out. Mounted on the end of the journal or shaft 24 for the 110 pulley 23^a and clamped to the side frame by suitable nuts 25 on the ends of said shaft are grooved cleat pulleys 26, 26^a. The ropes 19 and 20 may be connected to the respective yokes 22 on the frames in any suitable 115 manner, but we prefer to pass the end of the rope 17 through an opening 27 in the yoke 22^a, then carry it around the cleat pulley 26, thence around the end of the frame adjacent said yoke 22^a and around the cleat pulley 120 26^a, the extreme end portion of the rope 17 being connected to said rope by a rope-coupling 28, so as to provide a non-slipping connection between said rope 17 and the swinger frame. The connection described 125 provides for an adjustable connection between said rope 17 and the swinger frames so that the definite relation between the swinger frames heretofore described may be determined and maintained. The pulleys 130

26, 26^a, may be non-rotatably fixed in position on the shaft 24 by means of rivets 29 connecting the said pulleys and the side plates of the swinger frame.

5 The adjustable connection between the swinger frame and the line 17 also permits of the regulation of the length of said line to vary with different distances, greater or less, between the vessel and the dock.

10 We will now proceed to describe the actuating engine for taking up and paying out the hoisting lines 11, 12, and for actuating the ropes 19, 20, to traverse the swinging frames and thereby swing the hoisting ropes:—30, 31, designate hoisting drums mounted on suitable shafts 32, 33, and carrying respectively gears 34, 35, rigid therewith, said shafts being journaled in the side frames 36 and an intermediate member 37 of the engine structure. Extending parallel with the axis of revolution of the drums are driving shafts 38 arranged in longitudinal alinement and having bearing at their outer ends in pedestals 39, and at their inner ends in said intermediate frame member 37. Each of these shafts carries a driving pinion 40 meshing with the gears 34, 35, heretofore described, and also larger gears 41, each of which mesh with a driving gear 42 on armature shaft 43 of electric motors 44. The opposite ends of the armature shafts from the ends carrying the gears 42 are each provided with a friction disk or brake wheel 44^a with which coöperates suitable brake mechanism 45 operated by a solenoid 46 to positively grip and hold the armature shafts against rotation. Each of the motors is provided with its own controller 47 independent of the controller for the other motor, each controller including a rotary hand-operated shaft 48 adapted to be operated by a hand-lever 49 to control the supply of current to its motor. We do not deem it necessary to describe specifically the construction and operation of the controllers, but desire to state that they are preferably of a type wherein an intermediate position of the hand-operating lever cuts off supply of current to the motors, while forward movement of said lever causes supply of current to the motors to run them in one direction, and the rearward movement of the lever from intermediate position, serving to reverse the motors. Referring particularly to Fig. 4 of the drawings, it will be seen that the operating shafts 48 aline with each other and are provided at their inner ends with coupling extensions 50 having polyfaced ends 51 adapted to be connected by a coupling sleeve 52 provided with a tightening screw 53 by means of which said sleeve may be clamped in position. It will be understood that this sleeve is operable lengthwise of said shafts to couple them together to cause the controllers

to be simultaneously operated, or said coupling may be moved in the opposite direction to separate the controller shafts so that said controllers may be independently operated.

We preferably employ electric motors of the type capable of dynamic braking; that is, which, when over-speeded, generate current to retard rotation of the armature. This type is desirable in this system because the motor operates automatically to retard rotation of the drums when there is a tendency of the load to over-speed the same.

We will now describe a simple and preferred means for coupling the motor shafts so that the power of both motors may be exerted upon one of the drums. Mounted on one of the armature shafts 43 is an internally toothed clutch-member 54 preferably fixed to its armature shaft against movement longitudinally thereof, while, upon the opposite and alining armature shaft, is an externally toothed clutch-member 55 movable longitudinally of its shaft by a suitable operating means 56 to engage within, or be withdrawn from, the member 54. It will be understood that, when the member 55 is projected into the member 54, both armature shafts will be connected so that both motors exert their power upon one of the drums, and when the elements 54 and 55 are disconnected, each motor runs its drum independently of the other motor.

We may use an engine structure with the motor control and coupling feature, just described, for operating either the ropes 19 and 20 for swinging the loads, or for taking up and paying out the hoisting line 11, 12, but, under ordinary working conditions, the drums for the hoisting ropes and the motors therefor, are only connected when the hoist on the vessel and the hoist on the dock are practically equal, and it is not necessary to take into consideration any difference in the length of the hoisting ropes or the distance each is to travel. These motors and the drums may be coupled also when the load is too much for one motor, under which condition both motors may be connected to one drum to drive the same. The hoisting engines may be uncoupled when it is desired to work the loads independently and to gain speed under circumstances when it is desirable to lower and hoist the load carried by one rope while the other rope is held for any reason. It will be understood that the hoisting lines are wound on the drums of their engines in the same direction, while, as above stated, the lines 19 and 20 for the swinger frames are wound on their respective drums in opposite or reverse directions.

The engines for operating the rope-leads may be arranged at any point on the dock, but we prefer to arrange them side by side, as shown in Fig. 7, and mount the frame

of each on running wheels 57, adapted to travel on track rails 58, whereby the engines may be located at any desired point.

It will be understood that the ropes 19, 20 may be guided to their winding drums in any suitable manner dependent upon the location of the drums, but in the present embodiment we show them passing through blocks 19^a, 20^a beneath the engines, and 10 blocks 19^b, 20^b above the engines and from the latter to the drums. The blocks 14, 19^a, 20^a, and 19^b, 20^b, may be supported at any desired points on the dock.

15 The parts being as above described and in substantially the positions shown in the drawings, the operation of the apparatus is as follows:

As set forth, the connection 17 between the swinger frame is preferably definitely 20 fixed in length so that when one of the hooks or load-attaching or carrying devices on one of the hoisting ropes is in position to engage the load in the vessel, the other hoisting line is at the point of disconnection or 25 discharge. If it is then desired to lift a load from the vessel and transfer it to the dock and to return the disconnected hook on the dock to the vessel for another load, the operator throws the controller lever for 30 the motors for driving the hoisting drums, to cause the drums to wind up the lines 11 and 12, which operation is continued until the load carried by one of the lines, and the attaching device carried by the other 35 line, are elevated sufficiently to clear the ship structure, whereupon the operator of the swinger engine for controlling the swinging lines 19 and 20 throws the controlling lever for the motors to cause the drums 40 of the swinger engine driven thereby to take up the line 20 and pay out the line 19, which serves to traverse the swinger frame 16 to swing the rope 11 and its load outboard toward the dock and to pull on the 45 line 17 to traverse the swinger frame 15 and the line 12, engaged thereby, away from the dock toward the hatch of the vessel. During this traversing of the swinger frames the operator controlling the hoisting 50 ropes may pay out or take up the same simultaneously or independently to cause the load and the free hook to clear the vessel and to take the proper path of travel to expeditiously and accurately carry said 55 load and hook to their proper destinations. When the hoisting ropes have been traversed the desired distance, the hoisting engines may then be reversed by their controllers to pay out the lines to thereby deposit the 60 load carried by one line at its destination, and lower the hook carried by the other line into position to be attached to a new load. While in the positions just described the solenoid brakes may be operated to posi-

tively hold the lines in the positions to 65 which they have been moved. The load is then detached from the outboard hoisting line and the attaching device on the line in the hatch is attached to a load, whereupon the hoisting engines are again driven forwardly to lift the load and the empty hook, and the operator for the swinger engines reverses the revolution of the drums thereof from the direction heretofore described to 70 cause the rope 19 to be taken up by its drum and the rope 20 to be paid out, so that the pull on the rope 19 traverses the frame 15 outboard to swing the rope 12 toward the dock, and also to exert a pull on the line 17 to pull the swinger frame 16 and the hoisting rope 11 inboard to a point over the 75 hatch of the vessel. During this operation the hoisting lines may be, if desired or necessary, controlled, as heretofore described, by the operator for the hoisting line engines. The lines having reached the points of deposit and load-taking, the hoisting engine is then reversed to pay out said lines so that 80 the load is deposited at the proper point and the free hoisting line is lowered to a point where it can be conveniently attached to a load. While we have just described the invention as transferring the hoisting lines between definite points, it will be evident 85 that one of the hoisting lines may be taken up or paid out independently of the other at any point intermediate such definite points. 90

From the above description it will be apparent that we have provided a system in 100 which a given cargo may be transferred from a vessel to a dock, or vice versa, in approximately one-half the time which would be consumed with but one whip or hoist, and that a definite relation is maintained between the hoisting lines so that the operation of one to transfer a load simultaneously returns the other to be attached to a load. 105

If, during the operation of the system, it 110 should be necessary to lift a load in excess of the power of one of the hoisting engines, it is only necessary to connect the armature shafts by means of the coupling members 54, 55, and the controller shafts 48, 48, by 115 means of the sleeve 52, whereupon both of the motors will be controlled simultaneously to exert their combined power upon one of the drums, under which condition the drum not sustaining the excess load would be permitted to run free and take up its slack rope, it being understood that under these 120 conditions but one of the hoisting lines would be employed for load-lifting purposes. 125

It will be understood that we do not desire to be limited to the booms for supporting the hoisting ropes, and the swinging

ropes, as other supporting means may be employed within the intent and scope of our invention.

The hoisting or winding engine described herein and illustrated in Figs. 4, 5 and 6 is not claimed herein but is made the subject of a divisional application filed by us July 3, 1915, Serial No. 37,894.

What we claim and desire to secure by Letters Patent of the United States is:—

1. In a load transfer apparatus, in combination, an elevated support, a plurality of hoisting ropes suspended from said support, a swinger frame engaging the fall of each of said ropes, means for moving the hoisting ropes simultaneously in the same direction, and means for simultaneously operating the swinger frames.

2. In a load transfer apparatus, in combination, an elevated support, a plurality of hoisting ropes suspended from said support, a swinger frame engaging the fall of each of said ropes, means for moving the hoisting ropes simultaneously in the same direction, and means for simultaneously operating the swinger frames so that one moves in the opposite direction to the other.

3. In a load-transfer apparatus, in combination, an elevated support, two hoisting ropes suspended from said support, actuating means for simultaneously moving the hoisting ropes in the same direction, a swinger frame engaging the fall of each of said ropes, rope means for swinging said frames simultaneously in opposite directions to each other, and a pair of drums for operating said swinger rope means.

4. In a load-transfer apparatus, in combination, an elevated support, two hoisting ropes suspended from said support, a hoisting drum for operating each of said ropes, a swinger frame engaging the fall of each of said hoisting ropes, and means for swinging said frames in opposite directions.

45 5. In a load-transfer apparatus, in combination, an elevated support, two hoisting ropes suspended therefrom, a winding drum for each rope, a swinger frame engaging the fall of each of said ropes, each of said frames being provided with a swinger rope for swinging it in one direction, interconnected drums for operating said swinger ropes, and means for operating said drums simultaneously.

55 6. In a load-transfer apparatus, in combination, an elevated support, two hoisting ropes suspended from said support, winding drums for said ropes, connections between said drums, whereby said ropes may be paid out simultaneously and taken up simultaneously, a swinger frame engaging the fall of each of said ropes, a swinger rope connected to each of said swinger frames, and means for paying out one of said swinger

ropes and taking up the other of said 65 swinger ropes simultaneously.

7. In a load-transfer apparatus, in combination, an elevated support, two hoisting ropes suspended from said support, a winding engine for each of said ropes, connections between said engines whereby said ropes may be taken up and paid out simultaneously or independently of each other, a swinger frame engaging the fall of each of said ropes, and means for simultaneously 70 75 swinging said frames one in the opposite direction to the other.

8. In a load-transfer apparatus, two suspended hoisting ropes, a swinger frame engaging the fall of each of said ropes, a laterally disposed rope guide, a rope passing over said guide and having its ends adjustably connected to said swinger frames, a swinger rope connected to each of said swinger frames and extending in the opposite 80 85 direction from said last named rope, and means for taking up and paying out said swinger ropes.

9. In a load-transfer apparatus, in combination, a hoisting rope, a swinger frame engaging the fall of said rope, a swinger frame having a clean pulley thereon, a laterally disposed rope guide, a rope passing over said guide and having its end rove by said cleat pulley, a swinger rope connected to said 90 95 frame and extending in the opposite direction from said last named rope, and means for taking up and paying out said ropes.

10. In a load-transfer apparatus, in combination, an elevated support, two hoisting 100 ropes suspended from a common point on said support, a winding engine for each of said ropes, connections between said engines whereby said ropes may be taken up and paid out simultaneously or independently of 105 each other, a swinger frame engaging a fall of each of said ropes, and means for simultaneously swinging said frames in opposite directions to each other to swing said ropes laterally in opposite directions on said point 110 of common support.

11. In a load-transfer apparatus, in combination, a boom, two hoisting ropes suspended from a common point on said boom, a winding engine for each of said ropes, 115 connections between said engines whereby said ropes may be taken up and paid out simultaneously or independently of each other, a swinger frame engaging the fall of each of said ropes, and means for simultaneously swinging said frames in opposite directions to each other to swing said hoisting ropes laterally in opposite directions on said point of common support on said boom.

12. In a load-transfer apparatus, in combination, an elevated support, two hoisting ropes suspended from said support, a winding engine for each of said ropes, connec-

tions between said engines whereby said ropes may be taken up and paid out simultaneously or independently of each other, swinger rope means connected to the falls of said hoisting ropes and extended in opposite directions therefrom, and means for simultaneously operating said swinger rope means to swing said hoisting ropes in opposite directions to each other.

In testimony whereof I have hereunto ¹⁰ signed my name in the presence of two subscribing witnesses.

THOMAS SPENCER MILLER.
LOUIS G. RUGGLES.
